UNITED STATES PATENT OFFICE.

GEORGE W. LUNT, OF NEW BRUNSWICK, NEW JERSEY.

DESIGN FOR A CAP AND STOPPER FOR POWDER-BOXES.

SPECIFICATION forming part of Design No. 35,283, dated October 29, 1901.

Application filed July 6, 1901. Serial No. 67,370. Term of patent 7 years.

To all whom it may concern:

Be it known that I, GEORGE W. LUNT, a citizen of the United States, residing at New Brunswick, in the county of Middlesex and State of New Jersey, have invented and produced a new and original Design for a Cap and Stopper for Powder-Boxes, of which the following is a specification, reference being had to the accompanying drawings, forming part thereof, in which—

Figures 1 and 2 represent front and rear elevations, respectively, of my design; and Fig. 3 is a plan of the same.

As shown in the drawings, the leading or material features of my design consist of the ribbed upper portion, with the slightly-rounded top and the parallel-sided tubular part below the same, the parallel-sided neck, the inclined outwardly-tapering shoulders, and the inclined annular ribs and intermediate depressions below the shoulders, in appearance resembling a screw-thread.

The design of the upper or movable part comprises the parallel-sided tube *a*, the slightly-rounded top *b*, the annular ribs *c c'*, 25 and intermediate depression *d* between the said ribs. The design of the lower or attaching part comprises the parallel-sided neck *e*, the inclined outwardly-tapering shoulders *f*, the inclined annular ribs *g*, and intermediate 35 depressions *h*, the said ribs and depressions in appearance resembling a screw-thread.

What I claim as new, and desire to secure by Letters Patent, is—

The design for the cap and stopper for powder-boxes, substantially as shown and described.

In testimony whereof I have hereunto signed my name to this specification in the presence of two subscribing witnesses.

GEO. W. LUNT.

Witnesses:

J. F. CROPSEY,
AUGUSTUS WAGENER.
